UNITED STATES PATENT OFFICE

2,384,625

MEANS FOR GENERATING HELICES OF
VARYING DEPTH

John E. Kline, Grosse Point Farms, Mich., assignor to Micromatic Hone Corporation, Detroit, Mich., a corporation of Michigan

Application October 2, 1942, Serial No. 460,480

10 Claims.

(Cl. 51—59)

This invention relates to methods and devices for producing straight or helical grooves of varying depth and particularly to a method and device for rotating a machining element in predetermined relation to axial movement during the time it is advanced and retracted radially.

In the copending application of John E. Kline, Serial No. 455,712, filed August 22, 1942, and assigned to the assignee of the present invention, a method and device is illustrated for producing helices. The helices may be grooves of a gun barrel having helical lands therebetween, or may be splineways on the interior or exterior surfaces of a workpiece.

The invention of said application embodied a honing tool having one or a plurality of honing stones disposed on the angle of the helix on which the grooves are to be machined. A drum was provided on the head of the machine which moved the tool in rotation to have it follow the lead of the helix as the tool was axially advanced relative to the workpiece. A pair of cables were wound in opposite directions about the drum and were extended over pulleys on the carriage of the machine and secured at their ends to opposite ends of the machine. The alternating rotation produced by the axial movement of the tool conformed to the helix angle of the groove or grooves to be machined thereby. The advantage of using the drum over master lead bars resides in the fact that the honing could be accomplished on the present commercial machines, backlash was entirely eliminated, and no complicated or costly lead bar was necessary.

The invention contained in the above application is materially extended by the additional structure employed for varying the depth of the grooves as they are machined or finished by the honing stones of the tool. This has been accomplished by adding to the device, structure similar to that illustrated and described in the John E. Kline Patent No. 2,200,506, issued May 14, 1940, and assigned to the assignee of the present invention. This structure moves the adjusting element of the tool longitudinally to progressively change the radial position of the stones as the tool is advanced or retracted through the bore. The grooves honed in the gun barrel have greater depth at the breech end than at the muzzle end for the purpose of maintaining the seal of the rotating band of a projectile as effectively at the muzzle as at the breech. The area of groove is reduced in at least as great a degree as the wear of the metal of the ring in the groove as it approaches the muzzle of the

gun and will thus maintain a tight seal throughout the length of the gun barrel. This materially increases the muzzle velocity of the projectile by preventing the escape of the pressure gases and prolongs the effective life of the gun barrel.

Accordingly, the main objects of the invention are: to generate a helix by relating the reciprocation of the tool or work to its rotation and varying the radial position of the cutting elements thereof for varying the depth of the helical slot produced thereby; to hone helical grooves by a device having means for varying the depth of the grooves from one to the other end thereof; to hone a plurality of helical grooves in a workpiece while varying the radial positions of the stones to progressively vary the depth of the grooves from one to the other end of the workpiece; and in general, to provide a method and device for machining a groove of varying depth in a workpiece which is simple in construction, positive in operation, and economical of manufacture.

Other objects and features of novelty of the invention will be either specifically pointed out or will become apparent when referring, for a better understanding of the invention, to the following description taken in conjunction with the accompanying drawings, wherein:

30 Figure 1 is a broken plan view of a machine for honing helical slots of variable depth, which embodies features of the invention;

Fig. 2 is an enlarged broken sectional view of the adjusting and driving portion of the machine illustrated in Fig. 1;

Fig. 3 is an enlarged sectional view of the machine illustrated in Fig. 1, taken on the line 3—3 thereof;

Fig. 4 is an enlarged sectional view of structure, similar to that illustrated in Fig. 1, showing a further form of the invention; and

Fig. 5 is a view of structure similar to that illustrated in Fig. 1 showing a still further form which this invention may assume.

45 Referring to Fig. 1, a honing machine 10 is illustrated having a bed 11 on which a table 12 may be reciprocated. The table supports a driving head 13 having a recess in which a shank 14 on one end of a drum 15 is inserted for rigidly supporting the drum. The drum 15 rotates upon the shank 14 and is provided with a pair of sets of helical grooves 16 and 17 of the same hand. The grooves form a pair of sheaves upon which a pair of cables 18 and 19 are secured and are wound in opposite directions. The head 13 has

a bracket 21 secured thereto on which a plurality of pulleys 22 and 23 are pivotally supported on pins 24. The cables 18 and 19 extend over the pulleys 22 and 23, respectively, and their ends are secured to adjustable eye-bolts 25 and 26 at opposite ends of the bed 11. Nuts 27 on the end of the eye-bolts take up the slack in the cables 18 and 19 and retain them taut over the pulleys and about the sheave portions of the drum 15.

The drum is provided with a tool-receiving collet 28 in which the driving end 29 of the tool 31 is secured. The driving end 29 of the tool is hollow and an adjusting rod 32 extends therethrough, as illustrated more clearly in Fig. 2. The end of the adjusting rod abuts against the rod 33 which extends from the head 13 and is secured to the piston 34. The piston 34 operates in a cylinder 35 to center and provide stability to the rod 33. The structure for operating the piston in accordance with this invention will be explained more fully hereinafter.

The rod 32 extends through the universal joint 31 on the driving end 29 of the tool which is secured by pins 38 to the end of a driving tube 39. A pin 41 extends through the rod 32, through a slot 42 in the tube 39, and into an outer sleeve 43 which extends thereover. An internally threaded collar 44 is rotatably secured to the end of the sleeve 43 by a plurality of balls 45 which are retained in position by a collar 46 which is secured to the sleeve by pins 17. The threads 48 of the sleeve 44 engage the threads 49 on a sleeve 51 disposed over the tube 39. A pin 52 extends through a slot 53 in the tube 39 and through a block 54 disposed within the tube.

An adjusting rod 55 is threaded into the end of the block 54 extends the entire length of the tube 39 to the body of the tool containing the stones 36. A spring-pressed ball 56 secures the pin 52 against axial movement while a spring-pressed ball 57 is employed for retaining the sleeve 44 in adjusted position. By rotating the sleeve 44, the sleeve 51 is extended or retracted so as to extend or retract the adjusting rod 55.

The tube 39 is connected by a universal connection 61 to tool body 62 which has a series of apertures therein which are helically disposed with reference to the body axis. Stone holders carrying the stones 36 are disposed within the slots for radial movement. Within the body, tapered members are provided for engaging the stone holders and moving them outwardly when the rod 33 is advanced to the left as viewed in the figure. When the rod is moved in the opposite direction, the pressure on the stones is released and these may retract or be retracted by suitable spring means. The tool follows the construction of that illustrated and described in the copending application of J. E. Kline and C. S. White which was assigned to the assignee of the present invention.

A cradle 63 is employed adjacent to the end of the gun barrel 64 for receiving the end of the honing tool when the tool is withdrawn from the barrel. The extending frame 65 of the base 11 has a plurality of supporting brackets 66 upon which the barrel is clamped in substantially aligned relation with the tool 31. The universal connections at the driving head 31 and the tool body 61 permit the misalignment of the axis of the barrel with that of the tool during the honing operation. This eliminates the necessity of attempting to accurately align the axis of the shank 14 or its path of traverse with that of the barrel.

Referring to Fig. 4, a further form of the in-

vention is illustrated wherein the head 13 supports an arbor 71 on which a spider 72 is secured by keys 73. The spider carries a plurality of gears 74, preferably four or more in number, to form an even number of gears for a purpose which will be explained more fully hereinafter.

A housing 75 carries an internal gear 76, the teeth of which are in mesh with the teeth of the pinion gears 74. A sleeve 77 contains an external gear 78, the teeth of which are also in mesh with the pinions 74. The sleeve has a drum 79 secured thereto by keys 81 and has on its outer face the sheave portions 82 and 83, the leads of the grooves of which are both right or both left hand, depending upon the hand of helix to be generated. The sleeve 77 has an internally projecting pin 84 which extends into a helical groove 85, the lead of which is the same as the lead of the grooves in the sheaves so that the drum will advance along the arbor 71 to maintain the cable grooves in tangential alignment with the pulleys in 119 and 121 in all positions of the drum.

A set of radial thrust bearings 86 supports the housing 75 on the arbor 71 while the extending portion 87 of the housing has bearing relation with the sleeve 77. An adjusting rod 88 extends through the arbor 71, with one end abutting against the piston rod 33 in the head 13, the other end of which abuts against the adjusting rod 32 of the tool.

The pinions 74 are mounted on shafts 89, the ends 91 and 92 of which are mounted eccentric to the central body portion so that the axes of alternate pinions 74 may be annularly offset in one direction while other intermediate pinions 74 may be annularly offset in the opposite direction to bear against opposite sides of the teeth of the gears 76 and 78 so as to entirely eliminate any backlash which would otherwise exist therebetween. This adjustment is made by turning the shafts 89 at the heads 93 provided on the ends thereof.

A tool receiving adapter 94 is secured to the end of the housing 75 by pins 95. The driving end 29 of the tool may be secured in the head 94 in the same manner as the driving end was secured to the head 38 of the drum illustrated in Figs. 1 and 2. When a barrel is to have slots honed therein which are of considerable length of lead, one that would require a drum of large diameter if the structure of Fig. 1 were employed, the structure illustrated in Fig. 3 is utilized instead. The smaller drum 79 may make any number of revolutions during one revolution of the tool, depending upon the relation of the sun gear 78 to the internal gear 76 and the number of turns to be made within the length of the barrel. If a three to one relation exists between the rotation of the drum 79 and housing 75, then the nominal diameter of the drum 79 may be one-third that of the diameter of a drum which would be employed if a direct drive were utilized between the drum and the adapter 94. In this manner, the large cumbersome drum, which would otherwise be required, is eliminated.

Backlash will be entirely eliminated from between the cables and drum, by suitably tensioning the former, and also from between the gears by utilizing the sets of gears which may be offset in opposite directions to eliminate any play between the teeth. When the drum is rotated as a result of the advance of table 12, the gear 78 is caused to rotate and drive the pinions 74 on stationary axes and they in turn drive the ring gear 76 which rotates the housing 75 at a speed in pre-

determined ratio and in the opposite direction to that of the gear 78. This rotates the tool supporting adapter 94 and the tool in predetermined timed relation to the advancement of the table 12 and the tool 31.

Referring to Fig. 5, a drum 96 is illustrated having two sheave portions 97 and 98 which are of spiral helical form and which may be substituted for the drums 15 or 79 above referred to. One or a plurality of cables 100 are wound around each of the sheaves having one end of said cables secured thereto at the major diameter of one sheave and at the minor diameter of the other sheave and the other ends of the cables extending to the rear at the points 99 and 101. A drum of this particular type will progressively change the speed of rotation of the tool relative to its movement in reciprocation so that an accelerating or increasing lead may be provided to the grooves in the barrel of the gun, which is desirable in certain types of gun barrel construction. It is within the purview of this invention to vary the lead of the spiral angle of the sheaves so that the increase of the lead of the slot in the barrel will be variable rather than constant from the breech to the muzzle of the gun. The lands between such slots will produce very little turning of the shell near the breech and will increase to maximum turning at the muzzle. By having both of the sheave portions 97 and 98 exactly alike, whether they are of constant or variable spiral angle, the cables are maintained taut at all times so that no backlash will be present in the tool as it is reciprocated through the barrel.

Referring again to Figures 1 and 3, the piston 34 has a rearwardly projecting sleeve 101 in which a threaded stud 102 projects. A nut 103 locks the stud to the sleeve in adjusted position. A pipe 104 communicates with the cylinder 35 and is connected to a source of fluid under pressure by a flexible conduit 105. A suitable packing gland (not shown) seals the rod 33 in the forward end of the cylinder 35.

A bracket 114 carried by the head 13 has a dovetailed slot 115 in which the dovetail 116 of a carriage 117 is retained by a gib 118. A spring 119 urges the carriage 117 toward one side of the machine. A stud 102, projecting from the piston 34, has a head 121 which is bifurcated to receive a roller 122, the peripheral edge of which operates in a slot 123 in the carriage 117. The slot 123 is disposed at an angle and advances or retracts the stud 102 axially when moved transversely thereof. The carriage 117 has a stub shaft 124 on which a roller 125 is pivotally secured projecting therefrom on the end opposite to that against which the spring 119 engages. The roller 125 operates in a slot 126 on the angularly disposed face of a cam element 127 which has one end pivoted at 128 to the bed of the machine and the other end adjustably secured thereto by a bolt 129 which projects through a slot 121 therein. As the carriage 12 is advanced along the bed 11 of the machine, the roller 125, operating in the slot 126 of the cam element 127, will move the carriage 117 laterally of the bed against the tension of the spring 119. The roller 122 in the angularly disposed slot 123 in the carriage 117 will be advanced along with the stud 102 to the left against the pressure of the fluid from the pipe 104, in the direction of movement of the table 12, and will produce the progressive outward feeding of the stones 36 of the tool 62 as the tool is moved from the muzzle to the breech end of the gun.

When the movement of the table 12 is reversed, the carriage 117 will be urged toward the side of the machine on which the element 127 is secured and the fluid in the cylinder 35 will move the sleeve 101 and the head 102 to the right as the roller 122 is retained in the slot 123. This will progressively retract the abrasive stones as the tool moves from the breech end to the muzzle end of the gun barrel.

During the operation, the sleeve 44 of the adjusting portion 29 of the tool may be turned to produce increments of radial feed movement to the stones for increasing the depth of the slots being honed by the stones of the tool. This operation is continued until the depth of the groove at the breech end of the gun has reached the dimension after which the sleeve 44 is turned in the opposite direction to permit the abrasive stones to contract and the tool to be removed from the barrel.

The grooves within the barrel are disposed upon a desired helix, which may be constant throughout the length of the gun barrel or which may accelerate from the breech to the muzzle end, and vary in depth so as to be greater at the breech end than at the muzzle end of the gun barrel. The honing operation produces finished surfaces and maintains the desired width to the slots and to the lands which remain therebetween. While a gun barrel has been referred to specifically herein, it is to be understood that such reference was made by way of illustration and not for limiting the invention to this specific application.

What is claimed is:

1. The combination with a tool, of means for moving said tool axially, means for rotating said tool in timed relation to said axial movement, a radially adjustable element on said tool for machining a slot in said element as it is rotated and axially advanced, an axially shiftable member in said tool for adjusting said element, and means for engaging and shifting said shiftable member for progressively varying the radial position of said element relative to the tool axis during the advancing movement.

2. In a honing machine, a reciprocable carriage, a tool supported by said carriage, a radially adjustable cutting element on said tool, means for rotating said tool in timed relation and in opposite directions synchronized with the reciprocation of the carriage, an axially shiftable member in said tool for adjusting said element, and means for engaging and shifting said shiftable member continuously during the tool reciprocation for progressively moving the cutting elements of the tool radially in alternate directions timed to coincide with the alternate directions of movement of said carriage.

3. In a honing machine, a reciprocable carriage, a rotatable drum on said carriage, a honing tool rotated by said drum and having abrasive elements, a pair of cables having one of their ends secured to the machine and their other ends secured to said drum and wound thereon in opposite directions for rotating said drum and tool as the table is reciprocated, means for adjusting the abrasive elements of the tool radially, and additional means for progressively advancing said elements radially as the tool is moved in one direction of its cycle of reciprocation.

4. In a honing machine, a reciprocable carriage, a rotatable drum on said carriage, a honing tool rotated by said drum and having abrasive elements, a pair of cables having one of their

ends secured to the machine and their other ends secured to said drum and wound thereon in opposite directions for rotating said drum and tool as the table is reciprocated, means for adjusting the abrasive elements of the tool radially, additional means for progressively advancing said elements as the tool is moved in one direction of its cycle of reciprocation, and for progressively retracting said elements as the tool is moved in the opposite direction.

5. The combination with a tool having a radially movable machining element, means for reciprocating said tool, a drum connected to said tool, a pair of cables having one of their ends secured to the machine and their other ends wound about the drum in opposite directions for oscillatively rotating said tool when the tool is reciprocated, and means for radially advancing and retracting the machining element of the tool in timed relation to the direction of movements in reciprocation.

6. The combination of a honing tool having a plurality of annularly disposed helically positioned radially movable abrasive stones, means for reciprocating said tool, means for oscillatively rotating said tool in timed relation with its reciprocation, and means for progressively moving said abrasive stones toward and from the axis of the tool in timed relation to its directions of movement in reciprocation, said last means embodying an axially shiftable adjusting element carried by said tool which is continuously shifted by said moving means during the tool's movement in reciprocation.

7. The combination with a tool having a radially movable machining element, a drum for rotating said tool as it is moved axially, a gear unit disposed between said drum and tool for driving said tool at a different speed from that

of the drum, means for adjusting said machining element toward and from the axis of the tool in timed relation to the directions of movements of the tool in reciprocation.

5. 8. The combination with a tool having a radially adjustable machining element, a drum for rotating said tool as it is moved axially, said drum having a pair of like sheaves of spiral helical form for producing a varying speed of rotation of the tool relative to its longitudinal movements in reciprocation, and means for moving said machining element toward and from the axis of the tool in timed relation to its opposite movements in reciprocation.

10 15 9. The combination with a tool having a radially adjustable machining element, a drum for rotating said tool, said drum having a pair of like sheaves of spiral helical form, a gear unit disposed between said drum and tool, cables wound on said sheaves in opposite directions, and means for moving said machining element toward and from the axis of the tool in timed relation to its opposite movements in reciprocation.

10. In a honing machine, a reciprocable carriage, a head on said carriage, a drum on said head mounted for rotation relative thereto, a honing tool supported by said drum, radially adjustable abrasive stones carried by said tool, a pair of cables wound around the drum and secured at their ends for rotating the drum as the carriage is moved in reciprocation, a rod extending through said tool for adjusting the abrasive elements radially, and means for moving said rod for progressively adjusting the abrasive stones either outwardly or inwardly of the axis of the tool conforming to the direction of its cycle of reciprocation.

JOHN E. KLINE.
